TO LYON & HEALY, OF CHICAGO, ILLINOIS, A CORPORATION OF ILLINOIS.

PEDAL DEVICE FOR PIANOS AND OTHER PURPOSES.

1,374,890.

Specification of Letters Patent. Patented Apr. 12, 1921.

Application filed May 15, 1919. Serial No. 297,379.

To all whom it may concern:

Be it known that we, BENJAMIN H. JEFFERSON and WALTER I. KIRK, citizens of the United States, residing at Chicago, in the 5 county of Cook and State of Illinois, have invented a certain new and useful Improvement in Pedal Devices for Pianos and Other Purposes, of which the following is a full, clear, concise, and exact description, reference being had to the accompanying drawings, forming a part of this specification.

Our invention relates to pedal devices, such as are used for pianos and for other purposes.

15 One of the objects of the invention is to provide a pedal device of the class mentioned which can be acted upon at a point or position above the one which is usually or normally acted or pressed upon.

20 Another object of the invention is to permit the pedal device to be operated by acting upon it at such usual or normal position, as well as at such elevated point or position.

Another object of the invention is to secure these pressing surfaces at different 25 horizontal levels by means of a construction similar in general shape and character to the usual piano pedal.

Another object of the invention is to secure the different level pressing surfaces in a piano-pedal-like construction by adjustable devices contained largely within such construction.

Another object of the invention is to arrange for the easy, ready and quick adjustment of such relatively adjustable parts.

Another object of the invention is to secure simplicity and practicability of construction and operation.

40 Another object of the invention is to accomplish the foregoing and other desirable results in a simple and expeditious manner.

In the accompanying drawings Figure 1 is a front elevation of the lower part of the 45 front of a piano provided with three pedal devices embodying our present invention;

Fig. 2 is a vertical section taken on line 2-2 in Fig. 1;

Fig. 3 is a cross section taken on line 50 3-3 in Fig. 2.

Referring to the drawings, the front of a piano is indicated at 1 and there are three pedal devices shown numbered respectively 2, 3 and 4. The pedal devices 2 and 3 are in 55 condition to be acted upon and operated in

the manner normal or usual for piano pedals. The third pedal device, 4, is in condition to be acted upon and operated at a point above the normal or usual pressing surface.

Each of the pedal devices referred to consists of a rear portion or shank 5, (Fig. 2), which is firmly and securely mounted to the usual pedal bar 6 which is understood to extend to some part of the piano mechanism which will be actuated by the pedal device. Each pedal device also has a main or body part or pedal member 7, having a rear portion 8 which extends lengthwise of the shank 5, and a horizontal portion 9 extending forwardly from the portion 8. This horizontal portion 9 is preferably in the form of the usual piano pedal, so that its toe portion 10 provides a pressing surface which may be contacted with and acted upon by 75 the foot of the person playing the piano.

The body portion 7 is mounted so that it can be moved or swung upwardly to permit the toe portion 10 to provide an elevated pressing surface. As one arrangement said 80 portion 7 may be hinged or pivoted at 11 to the upper end of the shank 5 so that said member 7 may be swung about the pivotal connection 11 into an upwardly tilted position, as shown by dotted lines in Fig. 2. In 85 order to hold the member 7 in this elevated position, we provide a link member 12 pivoted at 13 to the pedal bar 6 and arranged to fit in a longitudinal slot or groove 14 in the member 7, as shown in Fig. 3. 90

This link 10 is provided with two recesses or notches 15 and 16 located at its opposite ends, and the pedal member 7 is provided with a pin 17. A spring 18 is arranged within the slot 14 above the link 12. The 95 rear end 20 of said spring 18 is inserted into a notch in the portion 8 and the front end 21 is arranged to move freely with reference to the member 17.

Thus when the pedal member 7 is in the 100 normal pedal position, as shown by solid lines in Fig. 2, the notch 15 in the link 12 will be in engagement with the pin 17 and the spring 18 will tend to hold said link in such engagement, thereby locking the pedal member 7 in such normal or lowered position. When, however, the link 12 is disengaged from the pin 17, by swinging said link 12 slightly up about its pivot 13 against the 105 tension of the spring 18, the pedal member 110

7 may be swung upwardly to the position shown in dotted lines in said Fig. 2. At the upper limit of said swinging movement, the pin 17 will come into engagement with the 5 notch 16 in the link 12 and the spring 18 will force said link into engagement with said pin, thereby locking the link 12 and the pedal member 7 in the upper adjustment, in which upper adjustment the upper portion 10 of the toe part 10 of the pedal device will form a pressing surface substantially above the pressing surface of the pedal device in its normal or usual condition.

As an arrangement for permitting the 15 engagement and disengagement of the link 12 with reference to the pin 17, said link 12 is provided with a shank 22 which projects downwardly and outwardly through the slot 14 so that an end portion is exposed so that 20 it may be pushed inwardly against the action of the spring 18 by means of the finger or thumb. Thus by pressing in the end 21 the link 12 may be disengaged from the pin 17, no matter in which of the notches 15 and 25 16 said pin is engaged, and when so disengaged the part 7 may be adjusted up or down as desired, to bring said part into its lowered or elevated position to provide the lower and upper actuating or pressing surfaces.

It will be understood that changes and modifications may be made without departing from the spirit of the invention.

What we claim is:

35 1. A pedal device having a pressing surface mounted for vertical adjustment and means for holding said surface in different adjustments, said holding means comprising a spring controlled link and a pin for 40 engaging a recess in said link.

2. A pedal device in the form of a piano 45 pedal, the rear end of which is pivotally mounted so as to permit the front end to be raised and lowered, and means for holding said pedal in different vertically adjusted positions, said pedal being provided with a recess below its pressing surface and said holding means being arranged within said recess.

3. A pedal device in the form of a piano 50 pedal, the rear end of which extends upwardly and is pivotally mounted at its upper end so as to permit the front end portion of said pedal to be raised and lowered.

4. A pedal device in the form of a piano 55 pedal, the rear end of which extends upwardly and is pivotally mounted at its upper end so as to permit the front end portion of said pedal to be raised and lowered, and means for holding said pedal in different 60 vertically adjusted positions.

5. A pedal device in the form of a piano 65 pedal, the rear end of which extends upwardly and is pivotally mounted at its upper end so as to permit the front end portion of said pedal to be raised and lowered, and means for holding said pedal in different 70 vertically adjusted positions, said means comprising a link pivotally mounted to the pedal support and a pin carried by the pedal 75 and adapted to engage a recess in said link.

6. A pedal device provided with an adjustable member hinged at its rear end so that its front end may be swung up and down to provide pressing surfaces at different horizontal levels, and means for locking said member in such different horizontal levels, said means comprising a pivoted link provided with notches and a pin on said member for engaging said notches.

80 7. A pedal device comprising a shank adapted to be secured to a pedal bar, an adjustable pedal member having its rear end hinged to said shank, a link pivoted to said 85 pedal bar and arranged within a slot or groove in said member, said link being provided with notches, and a pin carried by said member and extending across the slot or groove therein, said pin being positioned and adapted to engage the notches in said 90 link to lock said member in adjusted position, and a spring acting upon said link to hold it in locking engagement with said pin.

In witness whereof we hereunto subscribe our names this 24th day of April, A. D. 1919. 95

BENJAMIN H. JEFFERSON.
WALTER I. KIRK.
